UNITED STATES PATENT OFFICE.

HARRY H. BURTON, OF NEW BEDFORD, MASSACHUSETTS, ASSIGNOR TO DRAPER CORPORATION, OF HOPEDALE, MASSACHUSETTS, A CORPORATION OF MAINE.

WARP STOP MECHANISM FOR LOOMS.

Application filed July 21, 1926. Serial No. 123,959.

This invention relates to mechanical warp stop mechanisms for looms of that type wherein the detector bar has a detecting movement transversely of the loom.

5 In warp stop mechanisms of the type indicated the detector bar is usually associated with a detector bar holder which is held in fixed position, while the detector bar itself is given a detecting movement transversely 60 of the loom, and both the detector bar and detector bar holder are provided with a series 65 of teeth. It is usual in this general type of warp stop mechanisms to provide drop wires having elongated slots through which 10 the detector bar and detector bar holder extend and by which the drop wires are guided in their movements when released by a warp thread. When the drop wire is released by a 15 too slack or broken warp thread, it should engage between the teeth of the detector bar 20 holder and the similar teeth of the detector bar, whereby the latter is arrested in its transverse movement and loom stoppage is effected.

25 Where the drop wires are formed of sheet material, such as light sheet metal, the elongated slot is usually cut in the drop wire and is formed of substantially the same width throughout, and the top portion or 30 wall of the slot is usually formed on a curve or rounded. In such character of warp stop motion, a drop wire may not fall sufficiently far to engage the teeth of the detector bar, but the side portions of the elongated slot 35 where it rounds into the upper wall of the slot are liable at times to bind against the detector bar holder, of which there are usually two members, one at each side of the detector bar. Should this happen, as it does 40 at times, the loom will continue in operation, thus weaving imperfect cloth, due to the failure of the drop wire to pass completely into locking relation with the detector bar and detector bar holder.

45 It may happen at times, also, that lint will accumulate on the top of the teeth of the detector bar holder, so that if a drop wire falls it may not only bind against the side walls of the detector bar holder, but the lint itself 50 will at times prevent the top wall of the slot from passing into engagement with the teeth of the detector bar and the loom will continue in operation.

55 The object of the present invention is to provide a mechanical warp stop mechanism

wherein the detector bar has a movement transversely of the loom and is associated with a detector bar holder having similar teeth, both the detector bar and detector bar holder being passed through the drop 60 wires, each having an elongated slot for this purpose and having such slot widened at its upper portion, and provided with a straight wall connecting the side portions of the widened slot.

65 Preferably the drop wire is formed of sheet metal and the elongated slot which embraces the detector bar and detector bar holder is cut out by a die, and similarly the widened portion of the elongated slot at its 70 upper end is cut out to provide diverging side walls connected by a straight upper wall at the upper end of the widened slot thus formed.

75 In the drawings:

Fig. 1 is a perspective view of a portion of a warp stop mechanism provided with the present invention;

Fig. 2 is an enlarged cross-sectional view showing a drop wire normally held in raised 80 position during weaving;

Fig. 3 is a view similar to that of Fig. 2 showing the drop wire as having been released by a broken warp thread and the top 85 wall of the enlarged upper opening resting upon the upper surface of the teeth formed in the detector bar holder; and

Fig. 4 is a view similar to that of Figs. 2 and 3 but showing the drop wire as having fallen completely into locking engagement 90 with the teeth of the detector bar and detector bar holder, the upper position of the drop wire being indicated by dotted lines.

95 The warp stop mechanism with which the present invention is associated is of the type 100 wherein the detector bar has teeth and is given a detecting movement transversely of the loom, while the detector bar holder is a fixed element having similar teeth, and associated with the detector bar and detector 105 bar holder is a series of drop wires which are normally supported by the warp thread during weaving but which, when a warp thread breaks or becomes too slack, drop 110 into engagement with the detector bar and detector bar holder and arrest movement of the detector bar. The means for arresting the loom operation on the occurrence of a warp fault is not herein shown because it forms no essential part of the present in- 115

vention, which is more particularly concerned with the particular character of the drop wire.

In the drawings a support 1 (usually one at each side of the loom) serves as a means of sustaining the operating parts of the stop motion. The support 1, only one of which is shown, is provided with an opening into which extends the detector bar holder 2. 5 In the present instance of the invention, the detector bar holder 2 is formed in duplicate, and these are separated at their lower portions by a spacer 3, and in the spaces between the detector bar holder members 2 is 10 the detector bar 4. The detector bar holder 2 (whether there be one or more) may be suitably secured to the supports 1 by means of a bolt 5 which may pass through a slot 6 formed in the laterally extending portion 7 15 of the detector bar 4. The lateral extension 7 of the detector bar may be utilized as a means of associating the detector bar with mechanism for imparting movement transversely of the loom, but since the details of 20 such mechanism form no part of the present invention they are not herein shown.

The detector bar holder members 2 are each provided with teeth 8 which are herein shown as separated by a space 9, and each 30 tooth in the detector bar holder members is shown as of general rectangular form. Similarly the detector bar 4 is provided with teeth 10 and such teeth 10 are, as indicated in Fig. 1, spaced apart in a manner similar 35 to the teeth in the detector bar holder, but the upwardly extending teeth of the detector bar project slightly above the top surface of the teeth of the detector bar holder, the result being that should a drop wire (as 40 will later appear) be released by a broken or too slack warp thread, it may drop upon the top surface of the teeth of the detector bar holder and on the reciprocating movement of the detector bar it will be moved 45 into engagement between the teeth of the detector bar holder and thereby effect stoppage of the detector bar and the arrest of loom operation.

The drop wires 11, of which only one is 50 shown in the present illustration of the invention, may be of the usual hair pin type in which the downwardly extending legs 12 have a space 13 between them, through which may be passed a warp thread *a* for the 55 normal support of the drop wire during weaving, as indicated in Fig. 1.

The upper portion of the drop wire 11 is provided with an elongated slot 14, the side walls 15 of which are spaced apart a 60 sufficient distance to include between them the detector bar and detector bar holder, with the result that the parallel side walls 15 of the elongated slot act as guides in conjunction with the detector bar holder to 65 direct the movement of the drop wire.

The upper portion of the elongated slot 14 in the drop wire is of novel construction to insure engagement of the drop wire with the detector bar and detector bar holder teeth when a drop wire fails to be supported 70 by a warp thread.

As indicated, the upper portion of the elongated slot 14 is widened, a condition which may best be effected by cutting the metal of the drop wire divergently from the upper end portion 16 of the elongated slot at each side thereof, thereby producing at the upper extremity of the elongated slot the outwardly or divergent side walls 17 in the drop wire, the upper edge of said side walls being joined by a straight wall 18.

Should a drop wire be released by a too slack or broken warp thread, the divergent side walls 17 and the straight wall connecting the upper portions of the divergent side walls, insure that the drop wire shall pass fully into engagement with the teeth of the detector bar and detector bar holder. Should a drop wire 11, as indicated in Fig. 3, be released by a broken warp thread, while the top wall 18 of the widened slot is directly above the teeth 8 in the detector bar holder, the straight wall 18 will insure that it will rest upon the top surfaces of the teeth of the detector bar holder, so that when a tooth 10 of the detector bar meets the side of the straight wall 18, the drop wire will be pushed along the detector bar holder until it passes into the space between the teeth 100 thereof, whereupon loom stoppage is effected.

Should a drop wire be released by a broken warp thread when it is above the space between the teeth of the detector bar holder, it will fall directly between the teeth 105 of the detector bar holder, as indicated in Fig. 4, and upon engagement by the teeth of the detector bar will arrest movement of the latter and effect loom stoppage.

In warp stop mechanisms of this general 110 type, it sometimes happens that lint will accumulate on the top of the teeth of the detector bar holder which is stationary, and in such case the space formed by the diverging side walls 17 of the widened portion of the slot provides a pocket into which the 115 lint may readily pass when the drop wire is released by a broken warp thread.

The construction of the drop wire, as hereinbefore described, affords a sure and reliable means in a warp stop mechanism of the type indicated for effecting loom stoppage whenever a warp thread breaks or becomes too slack, and this is secured by the straight wall 18 at the upper terminal portion of the widened slot and the divergent side walls forming the widened slot above the elongated detector slot.

What is claimed is:

In a mechanical warp stop motion for 120

looms, the combination of a detector bar and detector bar holder each having rectangular teeth with straight upper supporting surfaces and rectangular spaces between, a series of drop wires each provided with an elongated detector slot having parallel side walls between which the detector bar and detector bar holder extend, and a top opening communicating with the detector slot and having upwardly diverging side walls, a straight top wall connecting the upper portion of the diverging side walls of said top opening and of a straight length greater

than the combined thickness of the detector bar and detector bar holder that the straight 15 top wall of the opening may engage and be supported by the straight upper supporting surfaces of the rectangular teeth of either the detector bar or detector bar holder upon the occurrence of a warp fault, and an opening independent of the top opening in drop wires for sustaining the drop wires upon the warp threads.

In testimony whereof, I have signed my name to this specification.

HARRY H. BURTON.
